UNITED STATES PATENT OFFICE.

SAMUEL L. BOGGS, OF IVANHOE, VIRGINIA.

ORE-SEPARATOR.

1,390,080.

Specification of Letters Patent. Patented Sept. 6, 1921.

Application filed October 16, 1919. Serial No. 331,014.

To all whom it may concern:

Be it known that I, SAMUEL L. BOGGS, a resident of Ivanhoe, in the county of Carroll and State of Virginia, have invented a 5 new and useful Improvement in Ore-Separators, of which the following is a specification.

This invention relates to apparatus for separating ore from gangue by the flotation 10 process.

The particular objects of the invention are to provide new and improved methods and apparatus for forming a froth adapted to take up the metallic constituents of ore, 15 while permitting the impurities or gangue to settle, and thus effecting separation. The apparatus is designed for more effectively producing the separating froth and for causing a positive circulation of the mixtures in 20 the apparatus, as will be more fully set forth. The advantages and the general operation of the device will be apparent from the following specification.

Referring to the drawings, Figure 1 is a 25 vertical longitudinal section; Fig. 2 is a plan view; and Fig. 3 is a plan view of the larger agitating element of the apparatus.

It is well known in the art that metallic constituents of ore may be separated from 30 the gangue thereof, by first pulverizing the ore, and then agitating it violently, in a mixture of oil and water adapted to form a thick froth, or suds. If the mixture of oil and water, or water and other element 35 adapted to produce the same effect, is correct, the froth formed will be sufficiently dense and strong to entangle the lighter metallic particles, while the gangue particles will not be retained, but will settle into the 40 water beneath the suds. This method has been practised for separating lead, tin, zinc, gold, and similar ores, and the general proposition above stated is not new.

The present apparatus has to do with 45 more efficient apparatus for carrying out such a process.

A main separation tank is provided having end walls 1 and 2, bottom 3 and sides 4. Above one end of this tank is a chute 5 50 adapted to feed the material to be separated to the tank. It will be understood that the ore is pulverized in a machine preliminary to being fed through the chute 5, and that is not a part of the present invention. Below the mouth of the chute is situated an inclined partition or baffle 6, which is at-

tached to the side walls of the tank, and is sloped to cause the powdered mixture of ore to be fed slowly into the main body of the tank through a narrow opening 7 immediately adjacent to the end wall 1, as plainly shown in Figs. 1 and 2. This feeding process is slow and the ore is thoroughly wet before passing through opening 7, by splash from the tank. Just beneath this opening 60 pipes 8 are led through the end wall 1. These are L-shaped, and have their vertical arms extending upward to a point near the point of the level of the top of the tank. Their function is to admit air to the compartment below member 6, as will be more 65 fully described below.

Near the bottom of the tank close to the end wall 1 is an agitator fixed on rotary shaft 9, which is adapted to be driven by 70 sprocket-wheel 10 connected to the chain 11, which in turn is driven by any suitable power device. On the other end of the shaft 9 is a fixed sprocket-wheel 12 adapted to drive a chain 13, which in turn drives rotary 75 shaft 14 by means of sprocket-wheel 15. Fixed on the shaft 14 and situated inside the tank is a second and smaller agitator. The main agitator, carried by shaft 9, is composed of outer paddle wheels 16, and 80 inner circular beating members 17 in the same plane and closer to the axis, as shown in Figs. 1 and 3. It will be observed that considerable space is left between these members through which water and the other materials may freely pass. Likewise the agitator on shaft 14 carries paddles 18 mounted 85 so as to leave an open space about the shaft 14.

The large agitator is mounted in a compartment A, formed by the end 1, bottom and sides of the main tank and by a partition consisting of a box-like member formed by boards 19, 20, and 21 extending 90 across the tank and fitted to each other and to the bottom and sides thereof in watertight relation. Just above this partitioning member there is a trough-like partitioning member composed of boards 22, 23, 24 and 25 extending from wall to wall of the main 95 tank. The board 25 is inclined upwardly toward its outer edge, and co-operates with partitioning board 26, likewise extending across the tank. The members 19, 20 and 21 form a dead space or chamber B, which 100 is not used. The members 22, 23, 24 and 26 form a supplementary agitation chamber or 105 110

trough C, which is open at the top to overflow from the main agitation chamber A, and which opens by the passage 27 formed between members 25 and 26, into the main body and settlement chamber D of the tank.

This latter chamber D is formed by the walls and bottom of the main tank and by an inclined bottom partition 30, extending from the bottom of the tank to a point near the top thereof, and having water-tight connection with the sides of the tank. At the upper end of the inclined bottom 30 the end wall 2 of the tank is cut away, leaving an overflow passage, controlled by gate 31, into

15 a spout or chute 32.

In the bottom of the main tank, leading from the chamber D there is a draw off pipe 32' fitted with a valve 33. This leads into a supplementary water-tight chamber E, attached to the bottom of the main tank. Leading from this compartment E is an inclined screw conveyer 34, inclosed in a suitable casing 35 and adapted to be driven by chain connection to sprocket-wheel 36 mounted on 20 the lower end of the conveyer shaft 37. In the bottom of the upper end of the conveyer casing 35 is an opening 38, having a spout 39 leading therefrom. The spouts 32 and 39 are placed to empty into any desired receptacles, as for example into another separation tank similar to the one just above described. This is for the purpose of continuing the process by subjecting the mixtures to additional separation in other tanks connected in series as shown in Fig. 1.

35 The operation of the apparatus is as follows:

A suitable mixture of water and oil, or other suds-forming materials, is placed in 40 the tank, preferably to about the level shown in Fig. 1. That is, to a point extending above the top of the board 20. Pulverized ore is fed through the chute 5 from a storage hopper, or pulverizing mill. It is introduced 45 slowly into the compartment A at the end of the tank, being wet by the splash therefrom. The shafts 9 and 14 are continuously driven. The form of the paddles 16 and round beating members 17, permitting the mixture to 50 pass freely therebetween, results in a very rapid and efficient agitation with resulting formation of suds, and a continuous and intimate mixture of the liquid, solid, and froth constituents. It will be observed that 55 both agitators turn clockwise. Therefore the lighter suds-contents are thrown continuously to the right, and liquid at the bottom of the tank is continuously and positively drawn to the left through passage E. The 60 suds are driven out of the chamber A over the walls 22 into the supplementary agitation chamber C, where an additional agitation takes place, and they are driven through the passage 27 out into the main compartment D. In this large space in which there

is no agitation, the gangue tends to settle out of the suds and to fall to the bottom of the mixture. It is drawn off through pipe 32' into the chamber E, and carried therefrom by the conveyer 34 to the outlet 38, as 70 will be readily seen. There will be a continual circulation of water through the passage F, from the main settlement chamber D into the main agitation chamber A, and likewise a continual circulation in the opposite 75 direction of the suds over the wall 22 and through the outlet 27.

A certain amount of the suds in compartment D will be continually driven out of that chamber when the gate 31 is removed. 80 It will be understood that the ore particles which have become entangled in, and are held by the suds are carried out the chute 32, and are then separated in the usual manner.

The process may be repeated as many 85 times as it is desirable in view of the character of the ore, in a series of similar tanks, of which only two are indicated in the drawings.

The apparatus described is particularly 90 efficient in that the agitator is designed to produce very rapidly a dense body of suds, in that a second and supplementary agitation is provided by the small paddle wheel, and in that the division of the tank and driven 95 agitators are adapted to produce a continuous circulation of the liquid mixture, and a continuous production and expulsion of the suds. The pulverized ore is added at a point so that all of it must be taken up by the agitation members and pass through the entire process. That is, there is no chance for preliminary settlement, and no chance for any particles to escape being subjected to the entire treatment. Air is admitted by 105 pipes 8 at a point where there is a constant suction, and at the place where it is most efficient in the production of suds.

I claim:

1. Apparatus for separating ore from 110 gangue, comprising a container, means to feed a mixture to be separated to the container, an agitating device situated in a compartment beneath the feed device, a supplementary compartment adjacent to the 115 first mentioned compartment extending across the tank and adapted to receive frothed material from the said agitating device and to discharge the frothed material into a main settlement chamber, an 120 agitating device situated in the supplementary compartment, a main settlement chamber beyond the supplementary compartment, the said main settlement chamber being connected to the first mentioned compartment by a passage beneath the supplementary agitation compartment.

2. Apparatus for separating ore from gangue comprising a fluid-tight container, an agitation device situated in a primary 130

- 1 agitation compartment, a supplementary compartment open at its top to receive frothed material from the primary agitation device and adapted to discharge same 5 into a settlement chamber, an agitation device in the said supplementary compartment, and a settlement chamber beyond said supplementary compartment, the settlement chamber being connected to the primary agi- 10 tating compartment by a passage beneath the supplementary agitation compartment.
3. An apparatus for separating ore from gangue comprising a container, said container being divided into an agitation com- 15 partment at one end thereof, a supplementary compartment extending across the container and open at its top to receive frothed material from the agitation compartment and adapted to discharge it into a settle- 20 ment chamber beyond, an agitating device in the supplementary chamber, and a passage beneath the supplementary chamber connecting the settlement chamber and the primary agitating chamber, said passage be- 25 ing intermediate the top and bottom of the main container.
4. Apparatus for separating ore from gangue comprising a compartment, an agitating device therein, a secondary compart- 30 ment open at its top to receive frothed material from the first compartment and adapted to empty into a settlement chamber beyond, an agitating device in the secondary compartment, and a connection between the 35 said settlement chamber and the primary agitation chamber, said connection extending beneath the secondary agitation chamber and being intermediate the top and bot- 40 tom of the settlement chamber.
5. Apparatus for separating ore from gangue comprising a main tank or container, said tank being divided into a primary compartment, a secondary compartment, and a settlement chamber, an agitation device in 45 the primary compartment, an agitation de- 50 vice in the secondary compartment, the secondary compartment being open at its top and adapted to receive frothed material from the primary compartment and to deliver said material to the top of the settlement chamber, the supplementary compartment extending across the main container between the primary compartment and settlement chamber and having its bottom intermediate 55 the top and bottom of the settlement chamber, a baffle beneath the bottom of the sec- 60 ondary compartment, said baffle extending upward to a point lower than the bottom of the secondary compartment to form an opening connecting the secondary compartment and primary compartment intermediate the top and bottom of the settlement chamber and beneath the secondary compartment.
6. In an apparatus for separating ore 65 from gangue comprising an agitating device and a settlement chamber, the combination of a secondary compartment positioned between the agitating compartment and settlement compartment and adapted to receive frothed material from the agitation compartment and to deliver it to the top of the settlement chamber, and an agitating device in the sec- 70 ondary compartment.
7. In an apparatus for separating ore 75 from gangue comprising an agitating device and a settlement chamber, the combination of a secondary compartment positioned be- 80 tween the agitation compartment and set- tlement compartment and adapted to receive frothed material from the agitation com- 85 partment and to deliver it to the top of the settlement chamber, and an agitating device in the secondary compartment, the second- 90 ary compartment being raised above the bot- 95 tom of the settlement chamber to permit re- turn flow of liquid from the settlement cham- 100 ber to the primary agitating compartment.
8. In an apparatus for separating ore 105 from gangue, a receiving compartment, an agitating device therein, a settlement cham- 110 ber, a partition separating the agitating compartment from the settlement chamber and extending upward from the bottom of said compartments, a supplementary com- 115 partment situated above the top of the par- 120 tition and leaving a space therebetween, said supplementary compartment being open at its top and adapted to receive frothed mate- 125 rial from the agitating compartment, an agitating device in the supplementary com- partment adapted to beat up the frothed mixture received from the first compartment and to deliver it to the top of the settlement chamber.
9. Apparatus for separating ore from gangue, comprising a container, means to feed a mixture to be separated to the container, an agitating device situated in a compartment beneath the feed device, a sup- 110 plementary compartment adjacent to the first mentioned compartment extending across the tank and adapted to receive frothed material from the said agitating de- 115 vice and to discharge the frothed material into a main settlement chamber, an agitating device situated in the supplementary com- 120 partment, a main settlement chamber beyond the supplementary compartment, the said main settlement chamber being connected to the first mentioned compartment by a pas- 125 sage beneath the supplementary agitation compartment, and means to draw off sediment from the bottom of the main settle- ment chamber.
10. Apparatus for separating ore from gangue comprising a fluid-tight container, an agitation device situated in a primary agitation compartment, a supplementary compartment open at its top to receive 130

- frothed material from the primary agitation device and adapted to discharge same into a settlement chamber, an agitation device in the said supplementary compartment, and
5 a settlement chamber beyond said supplementary compartment, the settlement chamber being connected to the primary agitating compartment by a passage beneath the supplementary agitation compartment, and

means to draw off material from the top and 10 from the bottom of the settlement chamber.

In testimony whereof, I have hereunto set my hand.
